UNITED STATES PATENT OFFICE

2,437,484

COOLING TOWER

Edward W. Simons, San Francisco, Calif., assignor of one-half to George W. Null, San Francisco, Calif.

Application January 22, 1945, Serial No. 573,899

9 Claims. (Cl. 261—109)

1

This invention relates to induced draft cooling towers and has for objects the provision of a more compact cooling tower having less height than heretofore without sacrificing the efficiency and which tower is more economical to construct and to operate than heretofore.

Heretofore cooling towers of the induced draft type have used horizontally extending louvres across the inlet openings inclined transversely at 45° to horizontal, the inclination being downwardly from the outer or leading edge of each louvre. This type of grid offers considerable resistance to the flow of air into the tower and necessitates the use of a relatively tall tower in order to provide for admission of the desired amount of air. The slope of the louvres is mainly for the purpose of reducing the drift loss which still occurs where there is a substantial wind.

With the present invention the drift loss is practically eliminated and the height of the air inlets is reduced about 55% as compared with the height of said inlets in the conventional tower using louvres, which reduction is directly reflected in the height of the tower and in the amount of materials used. Economy in operation of the tower and in its construction is the direct result of the reduction in the height, inasmuch as the reduction in the height of the air inlets does not reduce the efficiency of the tower.

Other objects and advantages will appear in the drawings and in the description.

In the drawings,

Fig. 1 is a part sectional, part elevational view of a tower of this invention, certain parts being more or less diagrammatically illustrated, such as the fan and motor.

Fig. 2 is an enlarged sectional view through a pair of the grid strips that extend across the air inlets at the lower end of the tower.

Fig. 3 is a sectional view showing one of the strips of Fig. 2 in plan view but broken in length.

Fig. 4 is a reduced fragmentary elevational view of a portion of the packing as viewed from the ends of the slats.

Fig. 5 is an elevational view of the slats of Fig. 4 broken in length and showing the end pieces holding the superposed rows of slats vertically spaced apart.

Fig. 6 is an enlarged fragmentary sectional view taken through several of the slats in an adjacent pair of rows showing about preferred proportions of the slats and spacings between slats and rows of slats.

In detail, the tower illustrated in the drawings is rectangular and has sheathing 1 on all four

2

sides within outside corner posts 2, thus providing four imperforate side walls. A fan 3 driven by a motor 4 is supported by a spider frame 5 or by any other suitable means within the upper open end of the tower for drawing air upwardly therethrough.

The corner posts 2 and posts 6 positioned intermediate the corner posts that are at the ends of two opposite sides of the tower support the packing within said tower spaced above the outer concrete walls 7' of a well into which the water drops from the packing. Said walls may be of wood or of other suitable material instead of concrete.

15. The posts 6 are inside the sheathing 1 and carry cross beams 7, 8 respectively above and below the packing, while corner posts 2 carry cross beams 9, 10 respectively, above and below the packing parallel with cross beams 7, 8.

20. Above the packing and at right angles to cross beams 7, 9 and below the latter are cross beams 11 supporting conventional water distributing pipes 12 that are connected with any suitable source of water, and below each of said pipes 25 is a splash strip 13. This structure is not new but is common in cooling towers.

The cooling tower illustrated is preferably oblong in plan view, which is a usual shape, and Fig. 1 shows it in elevation from one of the shortest sides. It will be noted that the roof 15 is cut away for the propeller.

At the lower end of the tower and below beams 10 are air inlets 16 that are in opposed spaced relation, said inlets being in the longer sides of 35 the tower and being defined by walls 7, posts 2 and beams 10, but they may be in the shorter sides. The shorter sides of the tower from beams 10 to the well walls are completely closed by the sheathing.

40. Midway between inlets 16 and the two outer walls 7 that define the lower sides of said inlets, the well is formed with a partition 17 which may be apertured to provide for communication between opposite sides thereof below the water level. Supported on this partition is a vertical baffle wall 18 that extends at its upper end between cross beams 8 that are carried by posts 6. This baffle is preferably imperforate, and as the packing in the tower is supported on beams 8, 45 10, it will be seen that the air entering either of the inlets 16 will all be directed upwardly through the packing and irrespective of the strength of any outside wind, there will not be any drift loss through said inlets.

50. The packing within the tower illustrated in

Fig. 1 comprises spaced superposed rows of horizontally extending spaced parallel slats 20 that are disposed in vertical planes with their greatest widths vertical. Thusly tiers of slats are provided and these tiers are arranged in two groups in Fig. 1 in opposite halves of the tower at opposite sides of a vertical plane extending through posts 6 and baffle 18. Obviously only one group of tiers or more than two groups may be used, if desired.

There are two parallel cross beams 8 extending across opposite sides of the posts 6 at the lower end of the latter, and which posts are preferably recessed to partially receive the beams leaving sufficient of their upper edges to support the end pieces generally designated 21 at one of the ends of the slats of each group of tiers, while end pieces generally designated 22 at the opposite ends of the slats of each group of tiers are supported on cross beams 10.

The end pieces that have been generally designated 21, 22 and which may also be called tiering strips, are identical at opposite ends of the slats, therefore the same numbers will be used for corresponding pieces. Said pieces at the ends of the slats are horizontal strips extending horizontally between opposite sides of the tower in its longest width, and which strips have their sides vertical and coplanar at said ends of the slats. They are arranged in pairs, the pieces 23, 24 at each end of the strips of each tier being complementarily notched at 25 (Fig. 4) so that each notch will receive substantially half of a tenon 26 formed at the opposite ends of each slat 20 when the adjacent edges of the pieces 23, 24 are together.

An inverted V-tongue and groove 27 are respectively formed on the adjacent edges of pieces 23, 24 respectively, to provide coplanar alignment of said pieces.

The pieces 23, 24 are preferably substantially uniform in vertical width and project above and below the upper and lower edges of the slats in the tier that they carry, said notches 25 being so spaced as to equally space the slats in each tier or row. The lower piece 24 of each pair 23, 24 is adapted to be supported at its lower edge on the upper edge of piece 23 of the pair of pieces therebelow, said adjacent edges being formed with the V-tongue and groove 27 the same as described for the edges of said pieces that are notched. Thus the adjacent tiers of slats are vertically spaced apart. However, the complementary notches 25 in alternate pairs of pieces 23, 24 are offset laterally so that the slats in adjacent pairs of tiers or rows are in staggered relation to each other. The degree of offset is preferably such as to position the slats of alternate tiers midway between the slats in the adjacent tiers, but above or below such adjacent tiers as the case may be.

The end pieces at one of the ends of the slats in each group of tiers is supported substantially against the sheathing 1, while the ends of the end pieces at the opposite ends of the slats are against posts 6. Thus the tiers of slats may be quickly and accurately built up within the tower, and each tier of packing slats with its pairs of end pieces 23, 24 (which may be termed a mat) may be assembled outside the tower for positioning within the latter.

Anti-warp means for preventing warpage of the slats is provided for in the form of a horizontal strip 30 that is notched at 31 along its lower edge to receive the upper edges of the slats 20 in each row when the said strip is laid across said slats

transversely thereof. (Figs. 4, 5). One such strip 30 for each row of slats is generally adequate, but more may be used if desired. Where one strip is used it is positioned intermediate the ends of the slats, and the notches are so formed as to relatively snugly receive the upper edges of the slats. These anti-warp strips are positioned on the slats of each successive mat as the latter are successively positioned in the tower.

10 The anti-warp means for the packing slats is desirable at all times but is particularly important where the slats are from resawn lumber. For example, where two packing pieces 0.375 inch thick are procured from pieces of one inch thickness. When such lumber is resawn it tends to warp due to the relief of tensions in the lumber.

In Fig. 6 is shown a preferred arrangement of slats 20 with respect to proportions and spacings, and which proportions and spacings are indicated in multiples of the letter "W," said letter referring to the width of each slat 20. As is indicated, where the vertical height of slats 20 is 10W or ten times the width of each slat, the spacing between tiers is preferably about 5W, or five times width W, and the center to center spacing between adjacent slats in each row is about 3.5W, or about three and one-half times the width of each slat 20. The width W is preferably about 0.375 inch.

The above spacings may vary. For example, the 30 vertical height of slats may be from about 6W to about 15W. The spacing between tiers may be from about one to seven or eight times the thickness W and the center to center spacing between slats may be from about three to about six times the thickness W. As the spacing between the tiers of slats decreases the space between adjacent slats in each tier will increase. The preferred proportions and spacings give the best results, particularly where the slats are rectangular in cross-section and are relatively thin. The most important provision is the spacing between tiers, but the importance of this spacing is dependent upon the other dimensions and distances set forth, hence the mere spacing of the tiers is not sufficient. It might also be added that the variations that may occur may be formulized and the relationship between spacings and dimensions shown in Fig. 6 will come within such formula.

50 Across each inlet 16 and spaced outwardly thereof, I provide a grid comprising a vertical row of horizontally extending, vertically spaced strips 35 (Figs. 1, 2, 3) each of which is disposed in a substantially horizontal plane.

Vertical end members 36 are provided with opposingly opening transverse recesses 37 that receive the opposite ends of said strips (Fig. 2) and vertical stop-strips 38 are secured to the members 36 in positions extending over the ends of said recesses for holding the strips 35 in said recesses.

60 Sheathing 39 between members 36 and the tower close the spaces between the said members and said tower, and the lower ends of members 36 may be supported on upward extensions 40 of the end walls 7' of the well that is below the tower.

The strips 35 in each grid are of streamline cross-sectional contour with the blunt end of such contour facing outwardly relative to the adjacent inlet 16 whereby there will be a minimum of resistance to the flow of air through the grids 70 into the tower. The specific contour preferred is an airfoil contour substantially corresponding with that known as NACA Airfoil No. 6521. The 75 contour shown in Fig. 2 is substantially identical

with this contour. The initials NACA refer to the National Advisory Committee for Aeronautics.

It is to be noted that the airfoil contour preferred has a concave lower surface (transversely of strip 35) which has good lift characteristics at zero angle of attack, and at zero angle of attack the coefficient of drag is low and the coefficient of lift is fairly high, being about 0.4. Other contours may be used, but the one shown in Fig. 2 and above described is preferred for the cooling tower of Fig. 1.

With the airfoil contour described, the upper surface of each slat has a slope inward to the tower, which slope would have an action comparable to that of a sill. This, together with the high wiping velocity generated over the upper convex surface of the strips 35 tends to convey any water that might be deposited on the strips into the tower.

The spacing between each of the grids and the tower is preferably about a foot in order that any tower drainage may find its way down the guiding surfaces of the tower posts and braces without contacting the grids themselves.

Anti-warp means may be provided for strips 35, which comprise a cylindrical dowel 41 driven through coaxial openings formed in the strips. With a driving fit, the dowel in each grid would tend to prevent any warping that might otherwise occur. Of course several spaced dowels may be used if desired.

While the cross-sectional contour of the dowel is not strictly streamline, it generally approximates such shape and it may of course, be of strictly streamline contour.

The spacing between the strips 35 may vary considerably, but where the width of each strip is between three and four inches and its maximum thickness is about $\frac{3}{4}$ inch, a spacing of between two and three inches is satisfactory.

In the tower itself, and between the fan and pipes 12, I may provide a drift eliminator in the form of a pair of adjacent horizontal rows of spaced oppositely inclined horizontally extending strips 42. The strips of these two rows coact to provide angularly extending passageways between the fan and the packing against the walls of which the air will wipe thereby depositing any surplus moisture on said walls for dropping back onto the packing. In many instances this drift elimination is not necessary but in other installations it is quite valuable.

It is to be understood that the illustrations and the foregoing description are not to be considered restrictive of the invention, but merely illustrative of a preferred form thereof.

I claim:

1. An induced draft cooling tower having imperforate side walls enclosing packing and having means for causing upward movement of air through said packing, a pair of spaced opposed laterally directed air inlets at the bottom of said tower for admitting said air into the lower end of said tower, a grid extending across each of said inlets, each grid comprising a substantially vertical row of vertically spaced horizontally extending strips each disposed in a horizontal plane and of airfoil cross-sectional contour with the blunt end of each such sectional contour facing outwardly relative to the inlet across which the strip extends, the lower surface of said airfoil contoured strips being arranged at an angle relative to a horizontal plane and sloping downwardly in the direction of the trailing edge thereof.

2. An induced draft cooling tower having im-

perforate side walls enclosing packing and having means for causing upward movement of air through said packing, a pair of spaced opposed laterally directed air inlets at the bottom of said tower for admitting said air into the lower end of said tower, a grid extending across each of said inlets, each grid comprising a vertical row of vertically spaced horizontally extending strips each disposed in a substantially horizontal plane and of airfoil cross-sectional contour with the blunt end of each such sectional contour facing outwardly relative to the inlet across which the strip extends, the upper surface of said airfoil contoured strips being convex and the lower surface being arranged at an angle relative to a horizontal plane and sloping downwardly in the direction of the trailing edge thereof.

3. An induced draft cooling tower having imperforate side walls enclosing packing and having means for causing upward movement of air through said packing, a pair of spaced opposed laterally directed air inlets at the bottom of said tower for admitting said air into the lower end of said tower, a grid extending across each of said inlets, each grid comprising a vertical row of vertically spaced horizontally extending strips each disposed in a substantially horizontal plane and of airfoil cross-sectional contour with the blunt end of each such sectional contour facing outwardly relative to the inlet across which the strip extends, the upper surface of each strip being convex, and the under surface of each strip being slightly concave in a direction transversely thereof from its point of greatest thickness toward the sharp end of each sectional contour.

4. An induced draft rectangular cooling tower having imperforate side walls enclosing packing and having means for causing upward movement of air through said packing, a pair of spaced opposed laterally directed air inlets at the bottom of said tower below two opposed side walls thereof and at a level below said packing, a grid extending across each of said inlets, each grid comprising a vertical row of vertically spaced horizontally extending strips each disposed in a substantially horizontal plane and of airfoil cross-sectional contour with the blunt end of each such sectional contour facing outwardly relative to the inlet across which the strip extends, the upper surface of said airfoil contoured strips being convex and the lower surface thereof being slightly concave in a direction transversely thereof from its point of greatest thickness toward the sharp end of each sectional contour.

5. An induced draft rectangular cooling tower having imperforate side walls enclosing packing and having means for causing upward movement of air through said packing, a pair of spaced opposed laterally directed air inlets at the bottom of said tower below two opposed side walls thereof and at a level below said packing, a grid extending across each of said inlets, each grid comprising a vertical row of vertically spaced horizontally extending strips each disposed in a substantially horizontal plane and of airfoil cross-sectional contour with the blunt end of each such sectional contour facing outwardly relative to the inlet across which the strip extends, a vertically extending anti-warp strip of streamline horizontal cross-sectional contour intermediate the ends of the strips in each grid securing said strips together to prevent warping thereof, the upper surface of said airfoil contoured strips being convex and the lower surface thereof being slightly concave in a direction transversely thereof from

its point of greatest thickness toward the sharp end of each sectional contour.

6. In an induced draft cooling tower having imperforate side walls and inlets at the lower end of said tower for admission of air into the latter, packing between said inlets and the top of the tower comprising superposed adjacent pairs of horizontal rows of horizontally spaced horizontally extending slats arranged in vertical planes with the slats in the rows of adjacent pairs arranged in staggered relation to each other, the said slats being of uniform vertical width and of uniform thickness, said width being between six and fifteen times the said thickness, the spacing between rows being between one and seven times said thickness and the center to center distance between the slats in each row being between three and six times said thickness.

7. In an induced draft cooling tower having imperforate side walls and inlets at the lower end of said tower for admission of air into the latter, packing between said inlets and the top of the tower comprising superposed adjacent pairs of horizontal rows of horizontally spaced horizontally extending slats arranged in vertical planes with the slats in the rows of adjacent pairs arranged in staggered relation to each other, the said slats being of uniform vertical width and of uniform thickness, said width being about ten times said thickness, the spacing between rows being about five times said thickness and the center to center distance between the slats in each row being about three and one half times said thickness.

8. In an induced draft cooling tower having imperforate side walls and inlets at the lower end of said tower for admission of air into the latter, packing between said inlets and the top of the tower comprising superposed adjacent pairs of horizontal rows of horizontally spaced horizontally extending slats arranged in vertical planes with the slats in the rows of adjacent pairs arranged in staggered relation to each other, the said slats being of uniform vertical width of and uniform thickness, anti-warp means securing the slats in each row together intermediate their ends, and a pair of superposed coplanar complementarily notched end strips at each of the opposite ends of the slats in each row securing said slats in spaced relation, and end portions of said slats being positioned in said notches and the adjacent edges of said strips being together.

9. In an induced draft cooling tower having imperforate side walls and inlets at the lower end of the tower for admission of air into the latter, packing between said inlets and the top of said tower comprising superposed adjacent pairs of horizontal rows of parallel horizontally spaced horizontally extending slats arranged in vertical planes with the slats in the rows of adjacent pairs arranged in staggered relation to each other, anti-warp pieces extending across the upper edges of the slats in each row transversely of the latter and formed with notches into which the said edges of said slats are fitted for preventing warping of the latter, said slats being of uniform thickness and of uniform vertical width and uniformly spaced apart in each row, means at the ends of the slats in each row spacing each adjacent pair of rows apart a distance between about four and about six times the thickness of each slat, the said thickness being from about one-eighth to about one-twelfth the vertical width of each slat, said means including spacing means for securing the slats in each row uniformly spaced apart from about three to about six times said thickness of each slat.

EDWARD W. SIMONS.
